UNITED STATES PATENT OFFICE.

JOHN B. PETERS, OF TOLEDO, OHIO, ASSIGNOR TO THE ELECTRIC AUTO-LITE COMPANY,
OF TOLEDO, OHIO, A CORPORATION OF OHIO.

BRUSH AND HOLDER FOR GENERATORS AND MOTORS.

1,222,982.

Specification of Letters Patent. Patented Apr. 17, 1917.

Application filed November 14, 1913. Serial No. 801,002.

To all whom it may concern:

Be it known that I, JOHN B. PETERS, a citizen of the United States, and a resident of Toledo, in the county of Lucas and State of Ohio, have invented certain new and useful Brushes and Holders for Generators and Motors; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to electrical apparatus and particularly to the construction of brushes and holders for generators and motors.

The invention may be embodied in different forms of constructions. One form of construction containing the invention, has been selected as an example to show how such constructions may be made and operated and is described in this specification.

25 Figures 1 and 2 are views of a brush set involving my invention.

The brushes 41 coöperate with the commutator of a motor or generator to form the collector of the electric current produced by rotation of the armature within a field or to connect the armature with an external circuit when driven by the current. The brushes 41 are secured to U-shaped arms 42 by means of the nuts and bolts 43. The arms 42 are provided with lips or flanges 44 which extend downward behind the brushes 41. The ends of the U-shaped arms are supported on pins 45. The pins 45 are mounted on an insulating yoke-shaped block 46. A coiled spring 47 is located between the ends of the U-shaped arms 42 and around the pins 45. The U-shaped arms are provided with segmental crowns 48. One end of each spring wire 49 is located between any two consecutive teeth of the crown 48 whereby the tension of the spring may be adjustably varied according to the location of the end of the spring. The ends 50 of the wires

press against the stop pins 51 located in the block 46. The pins 51 form stops for the 50 arms 42 and hold the ends of the wires 47 stationary while the other ends of the wires move with the segments 48. The brushes 41 are thus elastically pressed against the commutator 46. Perfect electric connections are made with the brushes by means of the flexible wires 52, having contact washers at their ends. The wires 52 are secured to the arms 42 and to the brushes 41 by means of the bolts and nuts 43. Insulating tubes 58 are 60 located around the pins 45 and wires 55.

What I claim as new, and desire to secure by Letters Patent, is,

1. In combination with a commutator, binding posts, a yoke of insulating material secured to the ends of the binding posts, pins extending into the yoke, arms having toothed segments, springs interposed between the toothed segments and the pins for pressing the arms toward each other, carbon block brushes secured to the ends of the arms, flexible connectors for connecting the binding posts with the carbon block brushes. 70

2. In combination with a commutator, binding posts, a yoke of insulating material secured to the ends of the binding posts, pins extending into the yoke, U-shaped arms pivotally connected to the binding posts and having an inwardly toothed segment, springs wound about the binding posts and located 80 intermediate the pins and the segments for pressing the arms toward each other, carbon block brushes secured to the U-member, a lip extending over one end of the brushes for holding the carbon block brushes in position, flexible connectors for connecting the carbon block brushes with the binding posts. 85

In testimony whereof, I have hereunto signed my name to this specification in the presence of two subscribing witnesses.

JOHN B. PETERS.
